UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,007,186.

Specification of Letters Patent.

Patented Oct. 31, 1911.

Application filed June 21, 1911. Serial No. 634,490.

To all whom it may concern:

Be it known that I, JOHN L. CREVELING, a resident of New York, in the county and State of New York, have invented certain new and useful Improvements in Electric Regulation; as set forth in the annexed specification and drawing forming a part thereof.

My invention pertains to that class of electric regulation wherein it is desired to regulate a dynamo or generator in a predetermined manner and in accordance with the duty to be performed thereby.

Figure 1 is a diagrammatic representation of one type of system of electric distribution comprehending my invention. Fig. 2 is a diagrammatic representation of a modified system comprehending my invention.

In the drawing, particularly Fig. 1, 1 represents a dynamo or generator provided with the usual field coil 2 having in series therewith the variable resistance 3, in this instance indicated as of the carbon pile variety. 4 is a lever normally drawn in an upward direction by the adjustable spring 5 and limited in its upward movement as by the adjustable screw 6. The lever 4 is provided at its extremity with the magnetic core 7 and it will be obvious that motion imparted to the core 7, by varying the resistance 3, may regulate the generator. 8 is a lever normally drawn in a downward direction by the adjustable spring 9 and has its motion limited in this direction by the adjustable screw 10. 11 is the positive lead of the generator and is connected with the positive side of the storage battery 12 and through the switch 13 with the positive side of the lamps or other translating devices indicated at 14. The negative terminals of the translating devices are connected with the wire 15 which is carried to one side of the translation circuit regulator 16 indicated in this instance as a resistance of the carbon pile variety. The opposite side of the carbon pile 16 is connected as by the wire 17 with one side of the automatic switch 18 which may be of any of the well-known varieties adapted to close the generator circuit when its voltage is substantially equal to that of the battery. The negative side of the storage battery 12 is connected to the main 17. The remaining terminal of the switch 18 is connected as by wire 19

through solenoid 20 with the negative brush 55 of the generator. The core 21 is attached to the lever 8 and normally drawn in an upward direction by excitation of the coil 20. The core 7 is surrounded by the solenoid 22 in shunt across the generator circuit in 60 such manner that excitation of the same tends to draw the core downwardly and increase the resistance 3. The coil 23 also surrounds the core 7 and is connected in shunt across the lamp regulator 10 in such manner 65 that current flowing in the coil 23 due to a drop in potential across the resistance 16 will assist the coil 22 in drawing the core 7 downwardly. The carbon pile 16 is operated by the lever 24 normally drawn in a 70 downward direction by the adjustable spring 25 and provided with a magnetic core surrounded by the solenoid 26 in shunt across the translation circuit.

In the system shown in Fig. 2 like numerals are used to designate like parts and the only difference between the two systems is that in Fig. 2 the coil 20 in series with the generator is suppressed and the coil 27 in series with the battery only used in its 80 stead.

The operation of my invention is substantially as follows: If the generator be running at a voltage sufficient to charge the storage battery, the switch 18 will be closed 85 and current will flow from the generator 1 through the field coil 2, resistance 3 and the generator may be regulated by proper manipulation of the resistance 3 in a well-known manner. Current will also flow from 90 the generator through the lead 11, storage battery 12, wire 17, switch 18, wire 19, and coil 20 to the generator and, if the speed of the generator be such that its voltage be sufficient to supply the maximum current 95 desired, I so adjust the spring 9 that if the generator tend to exceed this current, the coil 20 will lift the core 21 and raise the lever 8 against the action of spring 9 so as to increase the resistance 3 and prevent the 100 current output from exceeding this desired maximum. If, now, the battery be charged until the maximum voltage desired to have across the same is reached, I then so adjust the spring 5 that any further rise in voltage 105 will be prevented by the coil 22 drawing the core 7 downwardly against the action of spring 5 and thus depressing the lever 4 and

increasing the resistance 3 in a well-known manner. As this voltage cannot be exceeded, the current through the battery will, of course, fall off if the voltage of the battery increases further. If now the lamp switch 13 be closed and a load thus thrown upon the translation circuit, it is desirable that the generator be carried at a voltage below the maximum desired upon the battery in order that there will be less difference of potential between the supply circuit and the translation circuit which difference of potential between the two circuits is usually dissipated in the form of waste heat. I so adjust the spring 25 that when the maximum desired voltage across the translation circuit is reached, the coil 26 will raise the lever 24 and increase the resistance 16 in such manner as to hold the lamp voltage constant, and this, of course, will cause a drop across the resistance 16 which will increase as the voltage upon the translation circuit tends to increase. This drop across 16 will cause current to flow through the coil 23 which is wound to assist the coil 22 and the standard voltage which the coil 22 tends to hold across the leads throughout speed changes of the generator will be lowered and the generator may be thus controlled in response to voltage fluctuations at a lower voltage than the maximum voltage desired to have across the battery when there is no load upon the translation circuit.

The operation of the system portrayed in Fig. 2 may be readily understood from the operation above outlined with regard to the system shown in Fig. 1, it being only necessary to remember that the lever 8 in Fig. 2 is controlled by the coil 27 in series with the battery circuit only, while the coil 20 in Fig.

1 is influenced by the total generator output.

I do not wish in any way to limit myself to the exact details of construction or mode of operation set forth in this specification which merely illustrates an embodiment of my invention, for it is obvious that wide departure may be made in the way of details without departing from the scope of my invention which is as set forth in the following claims:

1. The combination with a generator, a storage battery, a translation circuit and a regulator for the translation circuit, of means for regulating the generator, means controlling said regulating means responsive to voltage fluctuations, means for controlling said regulating means responsive to current fluctuations and means for affecting the volt-

age responsive means affected by the operation of the translation circuit regulator. 60

2. The combination with a generator, a storage battery, a translation circuit and regulator for said translation circuit, of a generator regulating means, means for operating the said regulating means responsive to voltage fluctuations, means for operating the said regulating means responsive to current fluctuations and means for affecting the operation of the voltage responsive means affected by voltage variation upon the translation circuit. 70

3. The combination with a generator, a storage battery, a translation circuit and a regulator for said translation circuit, of a regulating element for controlling the generator, voltage responsive means for controlling said regulating element, current responsive means for controlling said regulating element and means for adjusting the point of operation of the voltage responsive means affected by the operation of the translation circuit regulator. 75 80

4. The combination with a generator, a storage battery, a translation circuit and a regulator for the said translation circuit, of a means for controlling the electromotive force of said generator, means for operating said controlling means for preventing the electromotive force of said generator from exceeding a predetermined limit, means for operating said controlling means for preventing useful current in a circuit supplied by said generator from exceeding a predetermined limit and means whereby the value of electromotive force held from being exceeded by the voltage responsive means is adjusted by the operation of the translation circuit regulator. 85 90 95

5. The combination with a generator having a field winding, a storage battery, a translation circuit and a translation circuit regulator, of means for controlling the generator comprehending a variable resistance in circuit with the field winding, means for controlling said variable resistance responsive to voltage fluctuations, means for controlling said variable resistance responsive to current fluctuations and means for affecting the operation of the voltage responsive means in response to operation of the translation circuit regulator. 100 105 110

JOHN L. CREVELING.
